**3-ETHYL-3-PHENYL-2,6-PIPERAZINEDIONE
AND DERIVATIVES THEREOF**

Sidney R. Safir, River Edge, N. J., and Joseph J. Hlavka, Cambridge, Mass., assignors to American Cyanamid Company, New York, N. Y., a corporation of Maine

No Drawing. Application October 8, 1954,
Serial No. 461,280

12 Claims. (Cl. 260—208)

This invention relates to a series of new organic compounds. More particularly this invention relates to 3-ethyl-3-phenyl-2,6-piperazinedione, N^1 and N^4 derivatives thereof, and methods for their manufacture.

The compounds of the present invention may be represented by the following general formula:

wherein R_1 is a member selected from the group consisting of hydrogen, lower alkyl, carboalkyloxy, carboaralkyloxy and acyl radicals, and R_2 is a member selected from the group consisting of lower alkyl, carboalkyloxy, carboaralkyloxy and acyl radicals, and R_2 is a member selected from the group consisting of lower alkyl and lower alkyl radicals. The terms "lower alkyl" and "lower carboalkyloxy" are used herein to include all alkyl and carboalkyloxy radicals containing from 1 to 6 carbon atoms such as for example methyl, ethyl, propyl, isopropyl, butyl, isobutyl, pentyl, isopentyl, hexyl, carboalkyloxy, carboethoxy, carbopropoxy, carbobutoxy, carbopentoxy and carbohexoxy. A suitable carboaralkyloxy substituent substitutable in the R_1 position is the carbobenzyloxy. As examples of suitable acyl radical substitutable in the R_1 position may be given acetyl, propionyl, butyryl and the like. Inasmuch as the parent compound 3-ethyl-3-phenyl-2,6-piperazinedione and the N^4 alkyl substituted derivatives thereof form addition salts with mineral acids, and the N^1 unsubstituted derivatives form metallic salts with alkali metal bases, it is intended that these salts also be included within the scope of the present invention.

The compounds of this invention are useful in the pharmaceutical field. We have found that they are particularly advantageous as anticonvulsants, being effective in varying degrees against seizures of both the grand mal and petit mal types.

The compounds of our invention can be prepared from previously known organic compounds by a novel series of chemical transformations which we have discovered. In these syntheses there are involved a number of new intermediate organic compounds and it is intended that these be included within the scope of our invention.

In accordance with our process, glycine ethyl ester is

5

2

condensed with propiophenone and hydrogen cyanide in ethanol to form alpha - carbethoxymethylamino - alpha-phenylbutyronitrile in accordance with the following equation:

15

This product may then be hydrolyzed with a mineral acid, for example, hydrochloric acid, to the corresponding carboxyamide:

20

25

30 The carboxyl group of the resulting alpha-(carboxymethylamino) - alpha-phenylbutyronitrile hydrochloride may then be esterified by treatment with a lower alkyl alcohol, such as methyl alcohol, to form the corresponding alpha - (carbomethoxymethylamino) - alpha-(phenylbutyramide) hydrochloride. Condensation of this product in the presence of sodium methoxide gives the desired 3-ethyl-3-phenyl-2,6-piperazinedione.

35 Cyclization of alpha - (carbomethoxymethylamino)-alpha-phenylbutyramide hydrochloride may be suitably effected in the presence of alkali metal alcoholates for example, sodium methoxide, sodium ethoxide, sodium isopropoxide; alkali metal amides, for instance, sodamide or the alkali metals, for instance, metallic sodium or lithium. We prefer to use sodium methoxide for this purpose.

40 The 3 - ethyl - 3 - phenyl - 2,6 - piperazinedione formed as a result of the cyclization is in itself an effective anticonvulsant agent. Other groups, however, may be conveniently substituted into either the N^1 or N^4 or to both the N^1 and N^4 positions to obtain a variety of equally efficacious anticonvulsants. For example, one may conveniently prepare the N^4 carboalkoxy substituted piperazinediones in accordance with conventional procedures.

45 The piperazinedione is dissolved in a suitable inert organic solvent such as acetone, benzene, chloroform, or dimethylformamide and the corresponding acid chloride is added thereto to obtain substitution of the desired radical. Alternatively, the introduction of an alkyl group into the N^4 position may be suitably effected by processes known in the art for the N-alkylation of amines. For example, to introduce the methyl group into the 4 position one may dissolve 3 - ethyl - 3 - phenyl - 2,6 - piperazinedione in acetic acid, treat the resulting solution with formaldehyde, and then with ethanol and platinum oxide catalyst in an atmosphere of hydrogen. In-

65

roduction of other alkyl groups may be advantageously effected by corresponding treatment. In a like manner, various methods known to those skilled in the art may be employed for introducing various substituents into the N⁴ and N¹ positions.

The following examples will serve to describe more particularly the invention contemplated by this disclosure although it is not intended that such examples be construed as limitations upon the scope thereof. All parts are by weight unless otherwise indicated.

Example I

200 grams of glycine ethyl ester hydrochloride was suspended in 80 ml. of hot anhydrous ethanol, and 81 grams of 95% sodium methoxide in ethanol was added. The mixture was stirred and filtered, and the filtrate was added to a solution of 192 grams of propiophenone in 350 ml. of liquid hydrogen cyanide at 0° C. This mixture was stirred at room temperature for 4 days.

The reaction mixture was concentrated under reduced pressure to a solid residue which was triturated with ether and filtered. The filtrate was saturated with dry hydrogen chloride at room temperature, and the oil which separated solidified on standing. The solid was filtered and dried to yield alpha-(carbethoxymethylamino)-alpha-phenylbutyronitrile hydrochloride, melting at 114° C. to 116° C. (decomp.). This crude product was evaporatively sublimed under reduced pressure giving a purified product melting at 121° C. to 123° C.

Example II

100 grams of alpha-(carboethoxymethylamino)-alpha-phenylbutyronitrile hydrochloride, the product of Example I, was added to 1 liter of ice-cold fuming hydrochloric acid, and the mixture was stored at room temperature for 1 day. The mixture was concentrated under reduced pressure at 45° C. to about one-half volume. The suspended solid was filtered and dried to yield alpha-(carboxymethylamino)-alpha-phenylbutyramide hydrochloride, melting at 210° C. to 214° C. (decomp.). A sample recrystallized from methanol melted at 212° C. to 214° C.

Example III

30 grams of alpha-(carboxymethylamino)-alpha-phenylbutyramide hydrochloride, the product of Example II, was dissolved in 1500 ml. of dry 3% hydrogen chloride in methanol. The mixture was stored at room temperature for 1 day and then concentrated under reduced pressure to a dry solid to yield alpha-(carbomethoxymethylamino)-alpha-phenylbutyramide hydrochloride melting at 218° C. to 221° C. (decomp.).

Example IV

A solution of 10.8 grams of sodium methoxide in 100 ml. of methanol was added to a solution of 27 grams (0.095 mole) of alpha-carbomethoxymethylamino-alpha-phenylbutyramide hydrochloride in 900 ml. of dry methanol. The solution was kept at room temperature for 45 minutes and then concentrated under reduced pressure to a dry solid. 95 ml. of cold 1 N aqueous hydrochloric acid was added to the residue, and the oil which separated was extracted with chloroform. The chloroform extract was dried with anhydrous magnesium sulfate and filtered, and the filtrate was concentrated under reduced pressure to a dry solid to yield 3-ethyl-3-phenyl-2,6-piperazinedione, melting at 114° C. to 115° C. A sample recrystallized from isopropyl alcohol melted at 114° C. to 115° C.

Example V

10 grams of 3-ethyl-3-phenyl-2,6-piperazinedione, the product of Example IV, was dissolved in 20 ml. of acetone, and 100 ml. of 90% carbobenzyloxy chloride was added. The mixture was kept at room temperature, and the solid which separated was filtered and dried. The

latter material is 7 grams of 3-ethyl-3-phenyl-2,6-piperazinedione hydrochloride. The filtrate was concentrated under reduced pressure to an oily residue which was crystallized from water-ethanol solution to yield 4-carbo-5 benzyl-3-ethyl-3-phenyl-2,6-piperazinedione, melting at 86° C. to 89° C.

Example VI

10 grams of 3-ethyl-3-phenyl-2,6-piperazinedione was dissolved in 20 ml. of acetic acid, and 7.6 grams of 37% formaldehyde and 10 ml. of ethanol were added. One-half gram of platinum oxide catalyst was suspended in the mixture while 1 liter of hydrogen was added. The mixture was then filtered, and the filtrate was concentrated under reduced pressure to an oily residue. The oil was taken up in isopropyl alcohol and 5.3 N ethanolic hydrogen chloride was added to pH 1, causing a solid to separate. The solid was filtered and dried in air to yield 3-ethyl-4-methyl-3-phenyl-2,6-piperazinedione hydrochloride melting at 201° C. to 204° C. (decomp.).

Example VII

3 grams of 3-ethyl-3-phenyl-2,6-piperazinedione was dissolved in 15 ml. of beta-ethoxyethanol, and 0.87 gram of sodium methoxide was added. The mixture was warmed to 60° C. and a solution of 2.6 grams of methyl iodide in 10 ml. of beta-ethoxyethanol was added dropwise with stirring. After the addition was complete, the reaction mixture was kept at 60° C. for an additional 10 minutes. The mixture was then poured into ice-water, causing a solid to precipitate. The crude product was filtered and dried to yield 3-ethyl-1-methyl-3-phenyl-2,6-piperazinedione melting at 104° C. to 106° C. A sample recrystallized from isopropyl alcohol, melted at 106° C. to 109° C.

Example VIII

3 grams of 3-ethyl-3-phenyl-2,6-piperazinedione was dissolved in 20 ml. of dry acetone, and 1.2 grams of phenoxycetylchloride was added. The mixture was refluxed for 3 minutes and then cooled. The precipitate, 1.6 grams of 3-ethyl-3-phenyl-2,6-piperazinedione hydrochloride, was filtered. The filtrate was concentrated under reduced pressure to an oily residue which was crystallized from isopropyl alcohol to yield 3-ethyl-4-phenoxyacetyl-3-phenyl-2,6-piperazinedione melting at 117° C. to 119° C.

We claim:

1. Compounds having the general formula:

wherein R₁ is a member selected from the group consisting of hydrogen, lower alkyl, carbobenzyloxy and phenoxycetyl radicals, and R₂ is a member selected from the group consisting of hydrogen and lower alkyl radicals; the acid addition, and alkali metal salts thereof.

2. The 4-lower alkyl-3-ethyl-3-phenyl-2,6-piperazine-diones.
3. The 1-lower alkyl-3-ethyl-3-phenyl-2,6-piperazine-diones.
4. The new compound 3-ethyl-3-phenyl-2,6-piperazinedione.
5. The new compound 4-carbobenzyloxy-3-ethyl-3-phenyl-2,6-piperazinedione.
6. The new compound 3-ethyl-4-methyl-3-phenyl-2,6-piperazinedione.
7. The new compound 3-ethyl-1-methyl-3-phenyl-2,6-piperazinedione.
8. The new compound 3-ethyl-4-phenoxyacetyl-3-phenyl-2,6-piperazinedione.

9. A method for preparing compounds having the formula:

wherein R₁ is a member selected from the group consisting of hydrogen, lower alkyl, carbobenzoyloxy and phenoxyacetyl radicals, and R₂ is a member selected from the group consisting of hydrogen and lower alkyl radicals; which comprises the steps of treating glycine ethyl ester with propionophenone and hydrogen cyanide to obtain:

treating said compound with a mineral acid to obtain:

contacting said compound with a lower alkyl alcohol under esterifying conditions to obtain:

15 cyclizing said compound in the presence of an alkali metal alkoxide to obtain 3-ethyl-3-phenyl-2,6-piperazine-dione and then treating said compound with a member selected from the group consisting of lower alkyl and phenoxyacetyl chlorides whereby the hydrogen atoms in the N¹ and N⁴ positions of 3-ethyl-3-phenyl-2,6-piperazine-dione are selectively replaced with a member selected from the group consisting of lower alkyl and phenoxyacetyl radicals.

20 10. A method as set forth in claim 9 wherein the mineral acid is hydrochloric acid.

11. A method as set forth in claim 9 wherein the lower alkyl alcohol is methyl alcohol.

25 12. A method as set forth in claim 9 wherein the alkali metal alkoxide is sodium methoxide.
